UNITED STATES PATENT OFFICE.

MAX FRIEDMAN, OF BALTIMORE, MARYLAND.

BELT REPLACER.

Application filed October 3, 1921. Serial No. 505,085.

To all whom it may concern:

Be it known that I, MAX FRIEDMAN, a citizen of the United States of America, residing in the city of Baltimore, State of Maryland, have invented certain new and useful Improvements in Belt Replacers, of which the following is a specification.

The difficulties incident to replacing belts on the pulleys from which they have slipped or been removed for any cause is well known to everybody familiar with conditions in shops where there are a large number of belt driven machines, or machines which though not strictly belt driven include some belt driven parts in their makeup. The replacement of belts has been accomplished with considerable risk of injury either by hand where the pulleys were accessible or by means of a pole or stick and the operation is known to require a degree of skill.

The present invention has to do with the provision of a belt replacer which can be used absolutely without risk and the operation of which requires no skill. The device of the invention while it may be adapted to a flat belt it is shown designed with particular reference to use in connection with round belts or chains.

In the drawings I have illustrated a belt replacer embodying my invention. In the drawings:

Figure 1 is a side elevation of the belt replacer, one of the rollers or pulleys being cut away for convenience of illustration, the handle and arm being broken away;

Figure 2 is a similar view of the handle and arm;

Figure 3 is a front view;

Figure 4 is a section at right angles to the plane of Figure 1;

Figure 5 is a plan on a reduced scale.

Referring to the drawings by numerals, the structure as shown includes a rod or arm 1, having a suitable grip or handle 2 at one end, and carrying at its other end secured to the rod a block or frame 3 having intersecting guide slots 4 and 5 at right angles to each other substantially at right angles to the arm and terminating adjacent the end of the block remote from the arm so as to form a stop 6. Mounted in the slots is a carrier 7 projecting through the said slots 4 and 5 and sliding substantially at right angles to the rod 1. The carrier 7 is provided with journals 10 on which are mounted two rollers 11—11, one at each

side of the guide block, the rollers having in their faces, shoulders or offsets 12 adjacent their neighboring or inner faces so that the two shoulders or offsets together form a groove or recess 14. Supported on the carrier parallel to the rod is a pivot or journal 15 for the gripper arms 16. There are two sets of grippers arranged in tongwise relation like a pair of pliers, one set of grippers being in front and the other in the rear of the guide block, the arms are crossed at the pivot and the corresponding arms are jointed above the block so that there is in fact one pair of tongs or grippers having two sets of operative ends or fingers 17.

In the form of the apparatus shown the carrier is apertured in a direction at right angles to the arm 1 and the block is provided with a pin also at right angles to the rod or arm 1, which pin is indicated by reference character 19, is set in the guide block, passed through the carrier acting as a guide for the carrier and there is a spring 20 bearing at its upper end against the end of the slot and at the lower end against the carrier which serves to normally force the carrier to the lower or outer end of the slot and there is a tension spring 21 joining the upper ends of the arms and tending to pull them together and close the grippers. The gripper arms as foresaid are crossed at the pivots and have neighboring curved portions just beneath the rod 1 having a cam or wedging action in connection with the rod so that when the carrier 7 sliding vertically in the slots, impelled downward or outward by the spring 20, is forced upward or toward the rod against the spring action, the gripper arms are forced apart opening the grippers and when the crossarms with the rollers and grippers move downward or away from the rod the grippers are closed by the spring 21 at their upper or rear ends.

The grippers are further controlled by an opening lever 23 pivoted intermediately of the main rod or arm 1, extending to a point adjacent the handle at one end and at the other end to a point adjacent the grippers and there is a slotted guide arm 24 extending upward from the block in which slot there is a sliding follower 25 having a foot plate 36 by which it is supported on the arm 24. The follower 25 is connected to the end of the controller arm by a connecting rod 26. This sliding follower 25 has pivotally connected to it two toggle arms 28 and

29 which are pivotally connected at their opposite ends one to the upper portion of each gripper arm so that they have a toggle action tending to spread the arms as the end 5 of the controller arm adjacent the handle is moved in opposition to the spring 21 which closes the gripper arms. This serves to open 10 the grippers to receive the belt. The lower end of the guide block is preferably grooved 15 as illustrated at 34 to engage the belt to pick it out of the grip of the arms in the replacing operation.

Also, the rollers 11 are hollowed out as to 20 their inner faces at 13 to receive and enclose 15 the gripper fingers 17. This makes it impossible for the fingers to come in contact 25 with the pulley in any position of the grippers. Also, the slot 5 being shorter than slot 4 limits the downward movement 30 of the slide block 3 relatively to the rollers.

In operation the belt 30 is placed in the grippers as indicated in Figures 1 and 3 and held by the spring action of the gripper as actuated by spring 21, the grippers being 25 opened for this purpose by means of the controller arm 23, it being understood that the belt is off of the driving pulley and either remains on or has been passed over the driven pulley, it is engaged by the belt replacer as just described, the operator holding the replacer or replacing tool in any 30 convenient manner as by the handle 2, places the belt in contact with the portion of the periphery of the driving pulley which is rotating away from the driven pulley and having brought the tool into such position that the groove 14 between the shoulders 12 of the rollers 11 on the tool, receives the peripheral portion of the pulley therein, presses 35 down on the tool toward the driving pulley presssing the rollers 11 against said pulley. This pressure received on the rollers 11 tends to move the carrier 7 on which they 40 are mounted backward or toward the arm 1, the carrier sliding in the slots 4-5, provided 45 for this purpose against the tendency of the spring 20. The motion of the carrier causes the grippers which are pivoted thereon to recede toward the arm 1 which in turn 50 causes the grippers to open by the cam action of the rod 1 or any suitable cam member which may be substituted therefor, engaging the intersecting portions of the arms at 32, see Figure 3, as the result the belt is released 55 in contact with the periphery of the pulley in a position which causes the motion of the pulley to carry the belt about its periphery seating it in driving position. As shown in Figure 4 the guide rollers and 60 block completely close the pulley groove preventing any displacement of the belt from the pulley and the grooved end 34 of the block pushes the belt out of the grippers.

The advantages of the structure are that it 65 not only provides a convenient engagement

of the belt without using the hands and thereby risking personal injury, but that it immediately releases the belt when the latter is brought in contact with the pulley eliminating all chance that the tool may be 70 yanked out of the hands of the operator and destroyed by sudden engagement of the belt with the driving pulley.

It will also be noted that the offset given to the handle or rod 1 as seen in Figure 5 75 keeps the hands of the operator out of contact with the belt.

I have thus described specifically and in detail a single embodiment of my invention so that the nature and operation of same 80 may be clearly understood, however, the specific terms herein are used descriptively rather than in a limiting sense, the scope of the invention being defined in the claims.

What I claim and desire to secure by 85 Letters Patent is:

1. A belt replacer consisting of an arm or handle, a guide mounted thereon, a sliding carrier cooperating with the guide and moving substantially at right angles to the arm, a roller on said carrier adapted to engage the belt pulley, and grippers pivoted on said carrier, a spring tending to maintain the carrier at the end of its traverse and cam means engaging the grippers tending 90 to open the grippers as they move in opposition to the spring and means tending to close the gripper arms.

2. A belt replacer consisting of an arm or handle, guiding means thereon, a carrier moving along the guide substantially at right angles to the arm, rollers on the carrier adapted to engage the belt pulley and grippers also mounted on said carrier, a spring tending to maintain the carrier at 100 the end of its traverse and cam means engaging the grippers tending to open the grippers as they move in opposition to the spring and means tending to close the grippers.

3. A belt replacer consisting of a guide, a manually controlled support therefor having an offset to avoid the belt, a carrier moving along the guide, grippers mounted on the carrier, a spring tending to move the carrier toward one end of the guide, means tending to close the grippers and means for opening the grippers as the carrier moves in opposition to the spring.

4. A belt replacer consisting of an arm or handle, a guide block mounted thereon having guide ways therein, a sliding carrier sliding in said block substantially at right angles to the arm, a roller on said carrier adapted to engage the belt pulley and gripper arms also mounted on said carrier, a spring tending to maintain the carrier at the end of its traverse and cam means engaging the gripper arms tending to open the gripper arms as they move in opposition to the 130

spring and means tending to close the gripper arms and means extending along the handle toward the end remote from the guide block for opening the gripper arms.

5 5. A belt replacer consisting of an arm or support, a guide mounted thereon, a carrier cooperating with the guide, jaws pivoted on the carrier, a spring tending to move the carrier toward one end of the guide, means

10 tending to close the jaws, means for opening the jaws as the carrier moves in opposition to the spring and means for opening the jaws by hand consisting of a pivoted arm extending along the support, a guide, a 15 follower moving on said guide, toggle arms pivoted on said follower and one connected to each of said jaw arms and means connecting said follower to said pivoted arm.

6. A belt replacer consisting of a guide, 20 a manually controlled support therefor, a carrier mounted to move along the guide, grippers on the carrier, a spring tending to move the carrier toward one end of the guide, means tending to close the grippers

25 and means for opening the grippers as the carrier moves along the guide in opposition to the spring.

7. A belt replacer consisting of a guide, a manually controlled support therefor, a

carrier cooperating with the guide, grippers 30 pivoted on the carrier, a spring tending to move the carrier toward one end of the guide, means tending to close the gripper arms and means for opening the gripper arms as they move in opposition to the 35 spring, a roller mounted on the carrier to move therewith and hollowed out to receive one of the grippers.

8. A belt replacer consisting of a guide, a manually controlled support therefor, a 40 carrier cooperating with the guide, grippers pivoted on the carrier, a spring tending to move the carrier toward one end of the guide, means tending to close the gripper arms and means for opening the gripper 45 arms as they move in opposition to the spring, a roller on each side of the gripper arms mounted on the carrier to move therewith, the rollers being hollowed out as to their adjacent lateral faces to receive the 50 grippers.

Signed by me at Baltimore, Maryland,
this 24th day of September, 1921.

MAX FRIEDMAN.
